CLAIM

The ornamental design for a light fixture, as shown and described herein.

DESCRIPTION

FIG. 1 is a top plan view of a light fixture showing my design;

FIG. 2 is a bottom plan view thereof; and,

FIG. 3 is a side elevation view thereof.

Due to the symmetric nature of the design, the left, right, front and back sides of the light fixture are identical, and, thus, only one view is shown herein.
